L. KELLNER

SAFETY PLUG AND LAMP SOCKET

Filed May 16, 1925

UNITED STATES PATENT OFFICE.

LOUIS KELLNER, OF CHICAGO, ILLINOIS.

SAFETY PLUG AND LAMP SOCKET.

Application filed May 16, 1925. Serial No. 30,824.

The main object of this invention is to provide a plug adapted to be screwed into the ordinary lamp socket and to form in said plug a terminal socket adapted to receive the ordinary standard threaded terminal cap of an incandescent electric light bulb; and to so construct the said plug and socket that the plug will be locked in the ordinary standard lamp socket and the lamp will be locked in the terminal socket, as described. The ordinary electric lamp bulb may be used in connection with the ordinary lamp socket, it being only necessary to interpose my safety plug and socket, connecting the plug to the ordinary standard lamp socket and screwing the lamp in the terminal socket of the plug.

Another object of the invention is to provide removable means in the form of a key for locking the several parts of the safety plug and socket together so that the lamp may be unscrewed therefrom, or the plug and socket may be unscrewed from the standard lamp socket.

While I have shown and described my invention used in connection with an electric light bulb, it is manifest that it may be used with any form of electrical connection, carrying terminal wires and adapted to have a threaded engagement with a socket having complementary contacts and terminals.

In the drawing Fig. 1 is a side elevation of an incandescent electric light bulb in position in the plug and socket, the plug and socket being shown in longitudinal sectional view;

Fig. 2 a side elevation of the connector sleeve;

Fig. 3 a side elevation of the terminal shell showing the insulating plug therein;

Fig. 4 a detail view of the removable key for locking the rotatable parts of the plug and socket together;

Fig. 5 a detail view of the retaining ring for holding the various parts assembled;

Fig. 6 a side elevation of the insulating retainer and guard; and

Fig. 7 a plan view of said guard.

Referring to the various parts by numerals, 1 designates a terminal shell which is formed of metal, preferably of brass. This terminal shell is substantially cylindrical at one end as at 2 and in this end is rigidly se-

cured a plug 3 of insulation, said plug projecting slightly beyond the free end of the cylindrical part of the terminal shell. The other end of the terminal shell is slightly enlarged in diameter and is internally threaded to form a terminal socket 4. The free end of the socket portion of the shell is expanded to form the outwardly extending inclined locking flange 5. The plug 3 is held in place within the end 2 of the shell 1 by having its outer end engaged by an in-turned flange 6 formed on the end of the shell and its inner end engaged by an annular rib 7 formed by crimping the shell inwardly. The plug 3 is formed with an opening 8 which extends longitudinally and centrally therethrough, the said opening being reduced in size at its inner end. A contact pin 9 is slidably mounted at its lower end within the opening 8 and disposed within the opening below the pin 9 and connected thereto is a coiled spring 10. The lower end of the spring 10 extends through the inner restricted end of the opening 8 and has a contact 11 connected thereto, said contact rests directly on the inner end of the plug 3 and is preferably slightly yieldable and is arranged in position to be engaged by the usual contact carried by the ordinary standard electric light bulb. The cylindrical plug portion 2 of the terminal shell is connected to the enlarged socket portion 4 thereof by a shoulder 12.

Surrounding the plug portion 2 of the terminal shell and loosely rotatable thereon is an externally threaded connector sleeve 13, said sleeve being threaded to adapt it to screw into the ordinary standard threaded lamp socket or plug receptacle. The connector sleeve extends beyond the outer end of the shell 1 and at its inner end it is formed with the enlarged annular lock flange or skirt 14. This flange extends to a point adjacent the flared end 5 of the terminal shell 1 and is connected to the body portion of the sleeve 13 by a radial shoulder portion 15. The shoulder portion 15 of the connector sleeve fits close to the corresponding shoulder 12 on the terminal shell.

A tubular guard and operating sleeve 16 of insulating material encloses the socket end of the terminal shell and the flange 14 of

the connector sleeve. An internal annular groove 17 is formed in one end of the guard and into said groove a split, resilient, retaining ring 18 is snapped. This retaining ring fits over the outer surface of the shoulder 15 of the connector sleeve and thereby locks the connector sleeve to the guard against longitudinal movement, but the connector sleeve and guard may be freely rotated independently of each other. The end of the tubular guard, adjacent the expanded end of the terminal socket 4, is formed with an inwardly extending annular stop flange 19 which is adapted to engage the lock flange 5 of the terminal shell. The stop flange 19 cooperates with the locking flange 5 of the terminal shell and with the lock ring 18 to lock the guard in position and hold it against longitudinal movement. The tubular guard and the connector sleeve are freely rotatable independently of each other; and when the connector sleeve is screwed into a socket, the terminal shell is freely rotatable in the connector sleeve. The lock flange or skirt 14 of the connector sleeve is formed at its free end with a slot 20 and the socket portion 4 of the terminal shell is also formed with a slot 21 adapted to register with said slot in the flange 14. The insulating guard 16 is enlarged at its end surrounding the slotted portions of the sleeve and terminal shell and extending longitudinally inwardly through said enlarged end is a key opening 22 which opens adjacent its inner end into the interior of the guard 16. A key 23 is provided for locking the terminal shell and the connector sleeve to the guard. This key is formed with an insulation handle 24 and a shank 25. The shank is formed with a recess 26 which opens through the side of the shank. A locking member 27 is pivoted in this recess the said member being formed with a locking head 28 at its free end. A spring 29 within the recess normally forces the free end of the locking member out of the recess so that the locking head 28 projects laterally from the shank of the key. The outward movement of the locking member is limited by a stop pin 30. The opposite lateral edges of the locking head converge outwardly to provide cam edges for a purpose to be presently described. The key is adapted to be inserted into the opening 22 in the guard 16 and through the slots 20 and 21 in connector sleeve and the terminal shell when they are in register in order to lock the three members of the device together against independent rotation and to permit them all to be rotated together.

The lamp bulb is provided with the usual threaded terminal cap 31 of standard size, and this threaded cap is adapted to be screwed into the terminal socket 4. The

usual terminal 32 of the lamp is adapted to 65 engage the contact 11 on the plug 3. One of the terminal wires of the lamp is connected to the contact 32 and the other is connected to the threaded terminal cap. When the connector sleeve is screwed into the ordinary lamp socket or plug receptacle, the said sleeve is in electrical contact with one of the terminals of the circuit and the contact 9 is in electrical engagement with the other terminal. As the connector sleeve is 75 in electrical contact with the terminal shell and the contact 9 is through the coiled spring 10 electrically connected with the contact 11, it is obvious that the lamp circuit will be completed in the usual way through 80 the contact 32 and the terminal cap 31.

When it is desired to screw the device into an ordinary threaded socket or a receptacle the key is inserted into the opening 22 in the guard. In inserting the key into the 85 opening one of the cam edges of the outwardly projecting locking head 28 will come in contact with the edge of the opening and be cammed thereby, against the resistance of the spring 29, back into the 90 recess 26 and within the compass of the shank of the key. The key may then be thrust to its innermost position. The parts of the device are then rotated to bring the slots 20 and 21 into register with the key 95 opening in the guard, whereupon the spring 29 will snap the locking head outwardly of the key shank and through the said slots thus locking all of the rotatable parts together. The connector sleeve may then be 100 screwed into the socket, and the lamp, or a similar threaded connector plug, may then be screwed into the terminal socket 4. To remove the key, the handle is simply given an outward pull causing the opposite cam 105 edge of the locking head 28 to strike the edge of the inner end of the key opening to cam the head 28 back out of the slots 20 and 21 and into the shank to provide clearance 110 for the withdrawal of the key. The guard and the terminal socket are thereby freed so that they may rotate on the threaded connector sleeve. It is obvious that when the key is removed the lamp cannot be unscrewed from the terminal socket, because 115 said socket will freely rotate in the connector sleeve. It is also obvious that the connector sleeve will not be rotated because of its frictional engagement with the threaded socket. The outer end of the threaded connector sleeve extends beyond the end of the insulating plug 3, and has suitably mounted thereon a stop ring 33 that is adapted to limit the inward movement of the connector sleeve into the socket 120 into which it is screwed. The contact 9 is normally thrust outwardly beyond the end of the stop ring 33 by the spring 10 so that 125

when the device is screwed home the said contact will be forced back against the resistance of the spring and the spring will hold it tightly against the fixed contact in the socket and a good electrical connection will be ensured. The yieldable contact 9 also adapts the plug to a socket of any construction. In order to prevent a short circuit between said fixed contact and the connector sleeve of the device, the stop 33 is made of insulating material. When the connector sleeve is screwed tightly into a socket the annular edge of the ring 33, firmly abutting the bottom of the socket, will prevent twisting or canting of the sleeve and will frictionally resist the unscrewing of the sleeve and prevent its unauthorized removal by a manipulation of the other parts of the plug connector.

20 A fault that is very common in devices of this character is that by means of canting or straining the lamp bulb to one side it is possible to cause the socket to frictionally bind, in which case the lamp may be unscrewed from the socket without the use of a key. This fault is overcome in the present invention by making the connector sleeve 13 materially larger than the terminal shell 1 as shown in Fig. 1. It is then impossible to cause the terminal shell 1 to frictionally bind in the connector sleeve 13 by canting the lamp bulb. The flange 5 extends outwardly to touch the inner side walls of the guard 16 and prevent the socket 4 from being forced against the surrounding skirt 14. This renders it impossible to unscrew the plug by inserting the thumb into socket 4 after the lamp has been removed, and pressing the socket 4 against the skirt 14 to frictionally bind it thereto. It will be seen also that owing to the use of a key that is inserted in a direction longitudinally of the device through a small opening and expanded laterally after it is inserted, it is much more difficult to improvise a key that will lock the parts together than is the case where a standard key insertable laterally of the device is used.

50 The forming of the guard 16 with an enlarged portion provides a shoulder 34 that is adapted to support a lamp shade.

What I claim is:

1. In a plug connector of the class set forth, a freely rotatable outer sleeve formed with a keyway extending longitudinally inward from the outer end of the sleeve and opening laterally into the interior of the sleeve at a point spaced from said end; and a laterally compressible and expandible key 55 adapted to enter said keyway when compressed and to expand through said lateral opening in the keyway when inserted to effect a locking connection with parts of the plug connector within the sleeve.

2. In a plug connector of the class set forth, a freely rotatable outer sleeve formed with a keyway extending longitudinally inward from the outer end of the sleeve and opening laterally into the interior of the sleeve at a point spaced from said outer end; 70 and a key adapted to be inserted into and removed from said keyway and formed with an insulation handle, a shank, and a spring-projected locking member normally extending laterally outward from said shank, the keyway being formed to receive the key only with the said locking member compressed and to permit the locking member to expand through its lateral opening into the sleeve when the key is inserted to effect a locking 75 engagement with parts of the plug connector within the sleeve.

3. In a plug connector of the class set forth, a freely rotatable outer sleeve formed with a keyway extending longitudinally inward from the outer end of the sleeve, said keyway being formed with a restricted mouth and opening laterally into the interior of the sleeve at a point spaced inward from said mouth; and a removable key formed with an 80 insulation handle, a shank, and a spring-projected locking member normally expanded laterally outward from said shank and adapted to be compressed inward, the restricted mouth of the keyway being formed to receive 85 the shank of the key only with the locking member compressed, the lateral opening of the keyway being formed to permit the locking member to expand into the sleeve to effect a locking connection with parts of the 90 connector plug within the sleeve when the key is fully inserted, and the locking member being formed with outwardly converging 95 cam edges adapted respectively to engage the inner and outer edges of the restricted portion of the keyway and cause the member to be compressed thereby to pass through the restricted portion when the key is moved longitudinally in either direction.

4. A plug connector comprising a holder 100 for a terminal contact; an internally threaded lamp socket carried by the said holder and rigid with it; an externally threaded connector sleeve surrounding the holder and freely rotatable relatively to it; means forming an annular insulating abutment and friction edge rigidly carried by the connector and spaced outwardly from the end thereof to abut the bottom of a socket into which the connector sleeve is screwed; a compressible terminal contact carried by the said contact holder and compressible longitudinally thereof; a freely rotatable guard and operating sleeve surrounding the lamp socket; and means to temporarily lock the lamp socket 105 and the connector sleeve to the operating sleeve to rotate with it.

5. A plug connector comprising a holder

for a terminal contact; an externally threaded connector sleeve surrounding said holder and freely rotatable relatively to it; insulation means forming an annular abutment and a friction edge rigidly carried by the connector sleeve and spaced outwardly from the end thereof to frictionally abut the bottom of a

socket into which the connector sleeve is screwed; and a spring projected terminal contact carried by the said contact holder and compressible longitudinally thereof.

In testimony whereof I hereunto affix my signature.

LOUIS KELLNER.
